UNITED STATES PATENT OFFICE.

ALFRED C. NELSON, OF LAKWOOD, AND EDGAR J. REILLY, OF YOUNGSTOWN, OHIO,
ASSIGNORS TO THE WILLIAM B. POLLOCK COMPANY, OF YOUNGSTOWN, OHIO, A
CORPORATION OF OHIO.

CAR.

Application filed July 21, 1922. Serial No. 576,454.

To all whom it may concern:

Be it known that we, ALFRED C. NELSON and EDGAR J. REILLY, both citizens of the United States, residing, respectively, at 5 Lakewood, Cuyahoga County, Ohio, and Youngstown, Mahoning County, Ohio, have invented a new and useful Improvement in Cars, of which the following is a full, clear, and exact description.

10 The present invention relates broadly to cars of the type adapted for the conveyance of hot metal, slag, cinder, and the like.

Cars of this character are usually referred to as "cinder" cars, and will be so 15 referred to herein, it being apparent that the word is an inclusive one.

It has heretofore been found that the most successful container for most purposes for use in cinder cars is a vessel in the 20 shape of a cone of substantially uniform section having a maximum diameter of about ten feet at the top, on account of railway clearances, and a depth of from seven to eight feet. These are usually 25 made of cast iron or steel of uniform section. Such containers have a much longer life, due to their ability to uniformly withstand contraction and expansion strains to which they are subjected.

30 Heretofore trucks have been built of sufficient strength to adequately take care not only of the transportation shocks to which they are subjected in cinder car work by the single pot or vessel which they carry, 35 but to take care of a considerably greater load. Such trucks have, however, to our knowledge, never been loaded up to capacity. This has perhaps been due to the fact that such cars have usually been built 40 of steel castings, thereby making it extremely difficult to handle more than one pot to a car. This has resulted in increased switching charges, which are made on the car basis, decreased locomotive efficiency, 45 high upkeep, and inefficient storage.

By the present invention these objections are obviated and there is provided a cinder car construction in which a plurality of pots may be carried by a single car.

50 It has also been customary in this art to provide the cinder cars with mechanism for tilting the pots to effect the desired emptying thereof. This mechanism has ordinarily been so constructed that a consid-

erable leverage has been exerted on the 55 trunnions in a manner producing a binding action. This has been true very largely by reason of the fact that a considerable overhang has existed between the point of power application and the trunnion. With 60 the construction provided herein, this overhang is reduced to a minimum and the efficiency of the operating mechanism is therefore materially increased.

In the accompanying drawings, there is 65 shown for purposes of illustration only, one embodiment of the present invention, it being understood that the drawings do not define the limits of the invention, as changes 70 may be made in the construction and operation therein disclosed without departing from the spirit of the invention or scope of our broader claims.

In the drawings,—

Figure 1 is a diagrammatic side elevation 75 of a cinder car constructed in accordance with the present invention;

Figure 2 is a top plan view, partly broken away, of the construction illustrated in 80 Figure 1;

Figure 3 is an end elevation of the construction illustrated in Figure 1;

Figure 4 is a top plan view, partly broken away, illustrating the pot supporting frame;

Figure 5 is a detail sectional view, on 85 an enlarged scale, of a portion of the actuating mechanism for tilting the pot frame;

Figure 6 is a sectional view, partly in elevation, on the line VI—VI of Figure 5; 90 and

Figure 7 is a detail view, partly in elevation and partly in section, illustrating a portion of the pot frame construction.

At the present time, switching charges 95 for cinder cars are based on the car basis. For this reason it is desirable to increase the capacity of each of the cars to as large an extent as may expeditiously be done. Cinder cars as usually constructed have an 100 over-all length of about twenty-three feet. By the present invention a cinder car having twice the capacity may be constructed with an over-all length of only 37 feet. This is of material advantage, as will be 105 apparent to those skilled in the art, as the length of the cinder runners may be correspondingly decreased. At the same time,

the up-keep of the cinder cars is materially reduced, as the capacity for the same number of cars is substantially double.

In the illustrated embodiment of our invention, there is shown a cinder car comprising supporting trucks 2 of any desired construction, such as commonly used. These trucks may be connected by spaced, parallelly extending longitudinal sills 3 tying the trucks together and maintaining the same in predetermined spaced relationship. The sills 3 may be braced in any desired and convenient manner by providing transversely extending braces 4 at suitable intervals. The sills 3 and the braces 4 may be generally of I-beam shape, thereby making it possible to utilize rolled material for this purpose.

Each of the trucks may be provided with a standard 5, each having formed on its upper surface a track 6 and an adjacent rack 7, such as frequently provided in cinder car construction.

In the present invention, instead of providing heavy steel castings for the pot frame, we preferably construct this frame also of rolled shapes. In the form illustrated, the frame may be composed of side beams 8 having their ends 9 inwardly curved and terminating in spaced relationship. Extending between the spaced ends of each of the side beams are end trunnions 10 comprising a casting having divergent arms 11 adapted to cooperate with the inturned ends 35 of the side beams and be secured to the webs thereof between the flanges. Each of these trunnions may have a circular bearing portion 12 adapted to have keyed thereto supporting wheels comprising flanged portions 13 for cooperation with the tracks 6, and gears 14 for cooperation with the racks 7. By reason of this construction, the ends of the frame may be caused to move in unison and the longitudinal axis of the frame maintained in alignment with the longitudinal axis of the car trucks. The arms 11 of the end trunnions may be braced by suitable webs 15 having curved inner surfaces 16 which preferably substantially correspond 50 to the curvature of the cinder pots.

At intermediate points, the side beams 8 are connected by transversely extending curved beams 17 secured to the side beams at their ends to provide a plurality of pot receiving openings in the frame. It will be apparent that the beams 17 are preferably curved to substantially conform to the curvature of the pots. The beams 17 may be braced in any desired manner at their central portions by braces 18, as clearly shown in Figures 4 and 7. After the beams and trunnions of the pot frame have been secured in position, we preferably cover the frame by securing thereto a top plate 19 having 65 spaced openings 20 therein, and a lower

plate 21 having spaced openings 22 formed therein. The openings 22 in the plates 21 are preferably of considerably less diameter than the openings 20 in the top plate, the difference in diameter being provided 70 in accordance with the different diameters presented in different horizontal planes by the cinder pots 23. These cinder pots may then be lowered into position in the frame, wherein they will be 75 held against movement by the top and bottom plates. The pots 23 may be provided with supporting lugs 24 on their sides to cooperate with the upper surface of the pot frame, and with locking lugs 25 to cooperate 80 with the lower surface thereof.

From the foregoing it will be apparent that we have provided a pot frame which may be largely constructed of rolled shapes, thereby enabling the same to be easily and 85 inexpensively produced, while affording the necessary strength to meet the load requirements and withstand transportation shocks.

For moving the pot frame laterally and thereby causing the gears 14 to roll in the racks 7 and effect a tilting movement of the pot frame, there may be provided on one of the trucks a suitable actuating motor 26. This motor may have a driving pinion 27 meshing with a gear 28 on the worm shaft 29 extending transversely of the truck frame and rotatably journaled in suitable bearings 30. The worm shaft 29 has secured to its outer end a spur gear 31 meshing with a similar gear 32 on a second worm shaft 33. Due to this construction it will be apparent that when the motor 26 is operated, the worm shafts 29 and 33 will be rotated in unison in opposite directions. The worms on these respective shafts extend in opposite directions, and each of the shafts is provided with an interiorly threaded nut 34. These nuts are formed with wings 35 adapted to slide in slots 36 in the actuating slide 37. This slide carries a pin 38 projecting therefrom and adapted to extend into the hollow bearing formed in the trunnion 10, as clearly illustrated in Figures 6 and 7. By this construction, rotation of the worm shafts will move the slide 37 in one direction or the other, this movement being transmitted through the pin 38 to one of the trunnions 10. This will tend to move the entire pot frame laterally, and this movement, due to the gear tracks, will effect the desired 105 tilting movement thereof.

By the provision of upper and lower worm shafts, arranged above and below the actuating pin 38, the overhang which exists between the trunnion mounting and the point of power application is reduced considerably beyond that which can possibly be obtained where a single worm shaft is utilized and located at the end of the actuating pin. By reducing this overhang, a 110 115 120 125 130

more efficient operation is secured, as the power required is cut down in proportion to the decrease in the friction. This correspondingly increases the length of life of 5 the structure and facilitates the dumping operation.

The advantages of the present invention arise from the provision of a cinder car having a plurality of cinder pots carried 10 thereby. Further advantages of the present invention arise from the provision of a pot frame constructed largely of rolled shapes and from the construction and operation of the supporting and actuating means there- 15 for.

We claim:

1. In a cinder car, a pot frame mounted for tilting movement and comprising side members having supporting trunnions secured thereto, and a plurality of pots carried by said frame, substantially as described.

2. In a cinder car, a pot frame having supporting wheels and mounted for tilting 25 movement and having a plurality of pot openings formed therein, and a pot mounted in each of said openings, substantially as described.

3. In a cinder car, a pot frame, top and 30 bottom plates secured to said frame, each of said plates having an opening therein, and a pot extending through said openings, said pot being removable from said frame and plates, substantially as described.

35 4. In a cinder car, a pot frame, top and bottom plates secured thereto, said plates each having a plurality of openings therein, the corresponding openings in the top and bottom plates extending in concentric 40 relationship, and a pot mounted in each set of aligned openings, substantially as described.

45 5. In a cinder car, a pot frame, means for tilting said frame, said frame having a plurality of pot receiving openings therein, and a pot mounted in each of said openings, substantially as described.

60 6. In a cinder car, a pot frame comprising side beams having converging end portions and trunnions secured between said end portions, substantially as described.

55 7. In a cinder car, a pot frame comprising side beams having converging end portions, transversely extending intermediate beams providing a plurality of pot receiving openings in said frame, and a pot mounted in each of said openings, substantially as described.

60 8. In a cinder car, a pot frame, trunnions for supporting said frame, an actuating pin for one of said trunnions, and independent means located above and below a portion of

said pin for effecting movement thereof, substantially as described.

9. In a cinder car, a pot frame having 65 supporting wheels and mounted for tilting movement, a plurality of pots carried thereby, and means for tilting said frame, substantially as described.

10. In a cinder car, supporting wheels, a 70 plurality of pots mounted for tilting movement on a common axis, and means for simultaneously tilting said pots, substantially as described.

11. In a cinder car, a pot frame, top and 75 bottom plates secured to said frame, each of said plates having an opening therein, a pot extending through said openings, and means for detachably securing said pot to said frame, substantially as described.

12. In a cinder car, pot supporting means having an opening therein, a pot extending through said opening, and pot supporting lugs carried by said pot and engaging the upper side of said supporting means, 85 substantially as described.

13. In a cinder car, pot supporting means having an opening therein, a pot extending through said opening, pot supporting lugs carried by said pot and engaging the upper side of said supporting means, and means carried by said pot and engaging the lower side of said supporting means for detachably securing said pot thereto, substantially as described.

95 14. In a cinder car, a pot frame, trunnions for supporting said frame, an actuating pin for one of said trunnions, a member operatively engaging said pin, and means for effecting movement of said member and pin and engaging said member upon opposite sides of said pin, substantially as described.

15. In a cinder car, a pot frame, trunnions for supporting said frame, an actuating pin for one of said trunnions, and means for effecting movement of said pin including a pair of actuating members located on opposite sides of said pin, substantially as described.

105 16. In a cinder car, a pot frame, supporting trunnions therefor, rolling supports for said trunnions, and actuating means operatively connected to one of said trunnions and located adjacent its rolling support, said actuating means including a pair of actuating members located on opposite sides of the axis of said trunnion, substantially as described.

110 In testimony whereof we have hereunto 120 set our hands.

ALFRED C. NELSON.
EDGAR J. REILLY.
